UNITED STATES PATENT OFFICE

ALFRED MOORHOUSE, OF DETROIT, MICHIGAN, ASSIGNOR TO PACKARD MOTOR CAR COMPANY, OF DETROIT, MICHIGAN, A CORPORATION OF MICHIGAN

INTERNAL-COMBUSTION ENGINE

Application filed January 7, 1929. Serial No. 330,741.

This invention relates to internal combustion engines and more particularly to the pistons used therein.

In order to reduce the reciprocating mass and improve the performance of such engines and particularly of engines used to propel motor vehicles and aircraft, it is common practice to employ pistons composed of light metals or metal alloys, such as aluminum and compositions of aluminum. On the other hand the cylinders of such engines are usually made of iron or steel, or are lined with such metals, and these metals expand under heat much more slowly than aluminum, so that the use of the lighter alloy pistons has been attended with certain difficulties in manufacture and operation. One of the principal difficulties is that if such an aluminum piston is a good fit in its cylinder when cold, it will expand sufficiently to stick in the cylinder when thoroughly warmed up from operation of the engine. For this reason such pistons are usually made a good fit at the higher engine temperatures, and consequently when operating at the lower engine temperatures they are loose and noisy, and subject to all the disadvantages of poorly fitted pistons. Moreover, such light pistons are relatively soft and are therefore easily scratched and scuffed.

One of the objects of this invention is to provide a piston which will obviate these difficulties and which shall secure the advantages of lightness of the aluminum piston together with the closer fit and better wearing qualities of pistons made of cast iron and other harder materials.

Another object of the invention is to provide a piston having a body of light metal which shall operate at all times out of contact with the cylinder wall, the contact and wear of the cylinder wall being taken by wearing elements or shoes of a material having a rate of expansion closer to that of the cylinder block than the rate of expansion of the piston.

Other objects of the invention will appear from the following description taken in connection with the drawings, which form a part of this specification, and in which:

Fig. 1 is a view in vertical section through a piston constructed in accordance with this

invention, taken on planes at right angles as indicated by the line 1—1 of Fig. 2;

Fig. 2 is a transverse sectional view, the sections being taken in different planes as indicated by the line 2—2 of Fig. 1, and

Fig. 3 is a perspective view of the spacing means for the ends of the shoes.

Referring to the drawing, the piston consists of a shell or body 10 of generally cylindrical shape, closed at one end by an integral head 11. This head 11 and body portion 10 are preferably formed of aluminum, or any of the well known aluminum alloys, in any convenient manner, usually by casting. It is provided with the usual bosses 12 in which are formed aligned holes 13 for the reception of the piston pin (not shown) by which the piston is operatively secured to the connecting rod of the engine in the well known manner. The bosses 12 may be provided with any suitable means for retaining the piston pin, such as grooves 14 near the ends of the holes 13, for the reception of a locking ring, not shown in this drawing. The bosses 12 may also be provided with conduits 16 by which lubricant may be conducted from the interior of the piston into the piston pin bearing.

Above the pin bosses 12 the body of the piston is provided with a number of circumferential grooves 17 for the reception of the usual piston rings 18, which are adapted to provide a sliding seal between the piston and the cylinder wall to retain the cylinder compression and to prevent the passage of lubricating oil in the well known manner. One or more of these rings may be provided with scraping edges to remove excess oil from the cylinder wall as will be readily understood. As construction of this nature is well known in the art to which this invention relates, further description thereof is unnecessary.

In the present invention the piston body 10 is intended to operate at all times out of contact with the cylinder wall, and for this purpose it is formed of a diameter somewhat less than the bore of the cylinder, so that when fully expanded under its maximum temperature, it will not touch the cylinder at any point. To properly guide the piston in

its reciprocating motion in the cylinder, and to prevent undue wear, suitable wearing members or shoes are carried by the piston body 10 to contact the cylinder wall. In the embodiment illustrated these members comprise segmental shoes 22 of channel-shaped cross section, the outer surface 23 of the web portion thereof being adapted to slide in contact with the cylinder wall to guide the piston 10 and to take the wear. These shoes 22 are preferably formed of material having a rate of expansion no greater than the rate of expansion of the cylinder block and preferably much less. A material suitable for this purpose, consisting of an alloy of iron and nickel, is well known under the name of invar steel, and has a coefficient of expansion considerably less than the coefficient of expansion of iron and steel.

To take the axial thrust of the piston body 10 on the shoes 22, the body is provided with spaced circumferential grooves 24 arranged in pairs above and below the pin boss 12, and preferably near the upper and lower ends 25 of the piston respectively. These grooves 24 are adapted to receive the flanges 26 of the channel shaped section respectively, the upper flange of each pair being a relatively close fit with its corresponding flange 26, while the lower groove is wider than its cooperating flange to provide for axial expansion and contraction of the body 10 with respect to the shoe.

Each of the shoes 22 forms a nearly complete semi-circular segment so that each pair of these shoes constitutes a nearly complete bearing ring for the piston. The ends of the segmental shoes 22 are spaced in any suitable manner, but preferably by means of 35 T-shaped spacing members 27 as illustrated. These members comprise a T-head of substantially rectangular section disposed between the upper and lower grooves 24 of each pair and adapted to separate the adjacent 40 ends of the semi-circular segments 22. These spacing members are provided with integral shank portions 28 adapted to seat in suitable 45 holes 29 provided in lugs 31 on the piston body 10.

In assembling these pistons in an engine, the shoes 22 are placed in position in their respective grooves 26. The shanks 28 are inserted in the holes 29 until the head portions of the spacers 27 are located between 55 the ends of the shoes, and in this condition the piston is inserted into its cylinder. After insertion in the cylinder radial movement of the shoes and the spacer members is limited by the cylinder wall which thus acts to retain 60 all the parts in position.

It will be observed that the only portions of the piston assembly in operative contact with the cylinder wall at any time are the outer surfaces 23 of the shoes 22, and the outer 65 wearing surfaces of the piston ring 18. As

these members are relatively small they add but little to the total mass of the piston. At the same time by reason of the slight expansion of the shoe members 22, all danger of sticking or binding of these wearing elements in the cylinder bore is obviated, while relative movement is permitted between the flanges 26 and the grooves 24, to accomodate the expansion of the light metal piston body 10.

While a specific embodiment of the invention has been herein described, which is deemed to be new and advantageous and may be specifically claimed, it is not to be understood that the invention is limited to the exact details of the construction, as it will be apparent that changes may be made therein without departing from the spirit or scope of the invention.

Having thus described the invention, what is claimed and desired to be secured by Letters Patent is:

1. A piston for internal combustion engines comprising a body of light expansible alloy of less diameter than the engine cylinder, and segmental metallic shoes having a rate of expansion less than that of the engine cylinder, supported on said body at the upper and lower edges thereof.

2. A piston comprising an integral head and body portion of light metallic alloy of less diameter than the cylinder bore to operate out of contact with the cylinder wall, wearing shoes of less expansibility than the cylinder walls comprising channel shaped segments carried by the body portion and engaging the cylinder walls, and means circumferentially spacing said segments.

3. A piston comprising a body portion having grooves and adapted to operate out of contact with its cylinder wall, segmental shoe members slideable on the cylinder wall and having flanges adapted to seat in said grooves, and means carried by said piston to space the ends of said segments.

4. A piston comprising a body portion having grooves and adapted to operate out of contact with its cylinder wall, segmental shoe members slideable on the cylinder wall and having flanges adapted to seat in said grooves, and means including T-shaped members having shanks carried by the body portion and having heads spacing the ends of the segments.

5. A piston comprising a head portion and an integral body portion adapted to support a piston pin, of substantially inexpandible shoes carried by the body above and below the piston pin and adapted to bear on the cylinder wall and retained in position on the body thereby, and piston rings carried by said body between the upper shoe and said piston pin.

In testimony whereof I affix my signature.

ALFRED MOORHOUSE. 130
